UNITED STATES PATENT OFFICE.

NEEDHAM H. BENEFIELD, OF DANVILLE, VIRGINIA.

COTTON-DRYING MACHINE.

1,068,845.

Specification of Letters Patent.

Patented July 29, 1913.

Application filed March 21, 1913. Serial No. 756,026.

To all whom it may concern:

Be it known that I, NEEDHAM H. BENEFIELD, a citizen of the United States, residing at Danville, in the county of Pittsylvania and State of Virginia, have invented new and useful Improvements in Cotton-Drying Machines, of which the following is a specification.

This invention relates to cotton drying machines, the object of the invention being to provide a machine whereby damp or wet cotton may be fed continuously along a determined path and dried without injury or danger of catching fire through the medium of a continuously circulating current or volume of hot air.

A further object of the invention is to provide simple, reliable and efficient means for heating, circulating and distributing the air for rapid drying action on the cotton.

The invention consists of the features of construction, combination and arrangement of parts hereinafter fully described and claimed, reference being had to the accompanying drawings, in which:

Figure 1 is a sectional elevation of a cotton drying machine embodying my invention. Fig. 2 is a vertical transverse section on the line 2—2 of Fig. 1. Fig. 3 is 30 a sectional plan view on line 3—3 of Fig. 1.

Referring to the drawings, 1 designates a suitable base or floor, upon which is supported a drying chamber 2 having an inlet 3 for the introduction of the moist or wet cotton and an outlet 4 for the discharge of the dried cotton. Arranged for travel longitudinally within the drying chamber between said inlet and outlet is an endless belt or apron 5, mounted on drums or rollers 6 and 7, the roller 7 having attached thereto a gear wheel 8. This gear wheel 8 meshes with a gear 9 with driving shaft 10 provided with fast and loose pulleys 11 and 12 for coöperation with a drive belt 13 receiving motion from any suitable source of power, whereby the apron 5 is in the drying operation continuously driven, but may be thrown into and out of operation whenever required.

Disposed within the top of the drying chamber is a hot air supply pipe 14, between which and the upper stretch of the apron 5 is arranged a divider 15, consisting of a screen or perforated plate, whereby the hot air discharged through the pipe 14 into the drying chamber is caused to

pass uniformly down through the perforations in the plate to act upon all portions of the cotton carried by the upper stretch of the apron 5, thus insuring the even supply of the hot air to the cotton and the even and regulated drying of the latter. The air is supplied to the pipe 14 through a conducting pipe 16 communicating at its outer end with a compartment or casing 17 in which is arranged a suction and distributing fan or blower 18. The casing 17 is in communication through a pipe 19 with a hot air furnace, heater or generator 20 of any suitable type, from which the hot air is sucked by the fan 18 and then forced through the pipes 16 and 14 into the drying chamber for distribution.

Arranged within the base of the drying chamber and in spaced relation to the floor 75 1 is a suction box 21 above and in spaced relation to which is a hood or deflector 22, of concavo-convex form, of less superficial dimensions than the suction box and having its concaved side facing the same. Communicating centrally with this hood is a suction pipe 23, connected by a return pipe or conductor 24 with a chamber or casing 25 in which is arranged a suction and discharge fan 26 communicating through a 85 pipe or duct 27 with the generator casing 20. The hot air impelled downwardly through the fibers of the cotton and belt and apron 5 is drawn by the suctional action of the fan 26 into the suction box 21 90 and into the space between the same and the hood 22, and through the pipes 23 and 24 to the casing 25, whence it is delivered back to the generator 20 to be heated over again, the air thus reheated being returned 95 to the drying chamber by the action of the fan 18, whereby a continual circulation of hot air through the drying chamber is produced.

The cotton to be dried is placed in a conical hopper 26' provided at the lower end thereof with a spur feed roller 27' partially projecting into the box or receptacle 28, into which hopper extends an inclined feed apron 29 provided with spikes or spurs whereby 105 the cotton fed into the hopper is loosened up and moved by the action of the roll 27' into engagement with the upwardly traveling stretch of the belt 29, the teeth of which engage and convey the cotton to the inlet 3, 110 through which it is deposited upon the adjacent end of the apron 5, and is thereby

carried through the drying chamber and delivered through the outlet 4 in a thoroughly dried condition to any suitable type of receptacle. The box or receptacle 28 may 5 serve as a tool holder, as well as to receive and save any small particles of cotton which may fall downward between the roll 27' and belt 29. The fans 18 and 26 and the roll 27' and apron 29 may be operated in practice 10 by any suitable type of drive gearing, which may receive motion from the same source of power as the belt 13.

From the foregoing description taken in connection with the drawings, it will be seen 15 that my invention provides a cotton drying apparatus whereby the cotton may be caused to travel continuously in a determined path and to be subjected in its travel to the action of a current or volume of hot air uniformly 20 supplied to uniformly and thoroughly dry the same, and whereby the continuous supply of a proper amount of air is insured.

I claim:—

1. In a cotton drying apparatus, the combination of a drying chamber having an inlet and an outlet, a cotton conveying apron arranged to travel in said chamber between said inlet and outlet, a hot air generator, means for supplying the hot air from the generator to the top of the drying chamber and uniformly distributing it down through the cotton on the apron, and means for exhausting the air from the bottom of the drying chamber and returning it to the 30 generator for reheating and recirculation.

2. In a cotton drying apparatus, the combination of a drying chamber having an in- 35

let and an outlet, an endless cotton conveying apron arranged to travel in said chamber between said inlet and outlet, means 40 for feeding cotton to the apron through the inlet, a hot air generator, a hot air supplying device in the top of the drying chamber, means for drawing hot air from the generator and forcing it through said hot air supplying device, a perforated screen disposed between the air supplying device and apron, and suction mechanism for withdrawing the air from the bottom of the drying chamber and returning it to the generator for re- 45 heating and recirculation.

3. In a cotton drying apparatus, the combination of a drying chamber having an inlet and an outlet, an endless belt arranged to travel in said chamber between said inlet and outlet, a hot air generator, an air supplying device in the top of the drying chamber, a perforated distributor between the same and the apron, means for drawing the air from the generator and supplying it to said supplying device, means for feeding the cotton to the apron through the inlet, a suction device within the bottom of the drying chamber including a hood, a suction pipe communicating with the hood, and means for withdrawing the air through said suction device and pipe and returning the same to the generator for reheating and recirculation. 55 60 65

In testimony whereof I affix my signature in presence of two witnesses.

NEEDHAM H. BENEFIELD.
